COMBINATION TYPEWRITER AND PERFORATOR

Bernard King, Los Angeles, Calif.

Application December 4, 1935, Serial No. 52,851

4 Claims. (Cl. 164—112)

(Granted under the act of March 3, 1883, as amended April 30, 1928; 370 O. G. 757)

This invention relates to typewriters and automatic transmitters or perforators for punching a tape in accordance with a predetermined code, and it has for its principal object an assembly of such instrumentalities in which the operation of one will cause the simultaneous operation of the other.

Another object of the invention is the provision of an assembly including a typewriter mounted in superposed relation with respect to a perforator and mechanism operatively connecting the keys of the typewriter with the corresponding keys of a perforator or transmitter, so that when the former are actuated the latter will be actuated automatically and simultaneously.

Still another object of the invention is the provision of an assembly of the character described embodying means operable at will for interrupting the operation of the perforator or transmitter without interfering with the operation of the typewriter.

A further object of the invention is the provision of an assembly of a typewriter and a perforator, or the like, in which one may be quickly 25 and easily moved to an inoperative position to provide access to the other for adjustment or repairs.

With these and other objects in view, as well as other advantages which may be incident to the use of the improvements, the invention consists of the parts and combinations thereof hereinafter set forth and claimed, with the understanding that the several necessary elements constituting the same may be varied in proportion and arrangement without departing from the nature and scope of the invention, as defined in the appended claims.

In order to make the invention more clearly understood, there are shown in the accompanying drawing means for carrying the invention into practical effect, without limiting the improvements in their useful application to the particular construction, which, for purposes of explanation, has been made the subject of illustration.

45 In the accompanying drawing:

Fig. 1 is a perspective view of a typewriter and perforator assembled in accordance with the present invention, and

Fig. 2 is a fragmentary, perspective view of 50 one of the rods operatively connecting corresponding keys of a typewriter and perforator or transmitter.

Referring to the drawing, an assembly embodying the present invention is shown as comprising a typewriter 10 having a keyboard, in-

cluding the usual keys 11, and removably secured to a frame structure 12, which is hinged at 13 to a table or other suitable support 14, and which houses a perforator or automatic transmitter 15 having a keyboard, including keys 16 the arrangement of which is the same as that of the typewriter 10. The perforator is mounted on the table 14 directly beneath the typewriter 10 with the keys 11 and 16 in vertical alignment. 10 The frame 12 includes two spaced parallel forwardly extending plates 17, each formed with a plurality of openings, in which rods 19 are mounted for vertical movement. The upper ends of the rods 19 are pivotally connected with the keys 11 of the typewriter 10 as at 20 (Fig. 2), and the lower ends are seated upon the corresponding keys 16 of the perforator 15 so that when the keys 11 of the typewriter are depressed the motion will be transmitted to the keys 16, and simultaneously cause a tape to be punched in accordance with a predetermined code.

It frequently occurs that certain portions of the subject matter being written by the typewriter should not appear in code on the tape. 25 To provide for such occasions, the typewriter and associated rods 19 may be swung upwardly out of operative relation to the perforator, by means of a treadle 21, which is pivotally connected at its rear end with the lower end of a vertically extending bar 22. The upper end of the bar 22 30 is connected with an intermediate portion of a lever 23 which extends laterally beneath the table and which is loosely connected therewith at one end, as at 24. The other end of the lever 23 is provided with a vertically extending post 35 25 for engagement beneath a lug 26, projecting laterally from the frame 12. When the operator wishes to prevent the operation of the perforator without interfering with the operation of the typewriter, he depresses the treadle 21, thereby elevating the bar 22, the lever 23, and the post 24. This swings the frame 12 upwardly about its hinge 13 a distance sufficient to elevate the typewriter 10 and associated rods 19 out of operative relation to the keys 16 of the perforator 40 without interfering with the operation of the typewriter. To avoid an undesirable drag upon the typewriter keys when the latter is in elevated position, the rods 19 are formed of a light weight material, such as aluminum, hard-rubber or the like. 45 Inasmuch as the lug 26 is not fixed to the post 25, the typewriter 10, frame 12 and parts carried thereby may be swung on the hinges 13 upwardly and to the rear of the perforator when the perforator only is to be used or to provide 50 55

access to the perforator for the purpose of adjustment or repairs. In such event the frame may be held in its elevated position by means of a prop 27, which is hinged at its forward end 5 to the table as at 28, and which is provided with a notch 29 at its rear end for engagement with the lug 26.

In conclusion it will be apparent this invention provides a structure by means of which a typewriter and a code transmitter, both of conventional design, are operatively combined so that the operator may produce a typewritten copy of the message to be transmitted at the same time that it is reduced to code by the code transmitter. Likewise, the instant invention enables the typewriter and its associated parts to be swung upwardly to the rear of the code transmitter and out of the way, but within convenient reach of the operator so that the latter, when occasion demands, may easily and conveniently restore the typewriter to its original operative position relative to the code transmitter, and finally this invention provides a foot pedal control wherein the typewriter and code transmitter may be temporarily disassociated without interfering with the continuity of action on the part of the operator relative to manipulation of the typewriter keys.

The invention described herein may be manufactured and used by or for the Government of the United States of America for governmental purposes without the payment of any royalties thereon or therefor.

What is claimed is:

33. 1. The combination with a typewriting and a perforating instrumentality for punching a tape according to a predetermined code, said instrumentalities having the same keyboards, of means carried by the typewriting instrumentality to 35 operatively connect the keys of the latter with those of said perforating instrumentality whereby the actuation of the keys of said typewriting instrumentality will cause the simultaneous actuation of the corresponding keys of the perforating instrumentality, said means including a hinged frame structure adapted to support the typewriting above the perforating instrumentality, a horizontally disposed guide member carried by the frame structure, said member being vertically spaced from and overhanging the keyboard of the perforating instrumentality, and having therein a plurality of perforations, a series of rods extending through the perforations in the guide member, said rods having their upper extremities pivotally connected to the keys of the typewriting instrumentality and their lower ends disposed in operative relation with respect to the corresponding keys of the underlying perforating instrumentality, a foot-pedal 45 controlled means in connection with the frame structure to effect elevation of said structure and temporarily disassociate the connection between the keys of the two instrumentalities, whereby to permit operation of the keys of the typewriting instrumentality without consequent actuation of those of the perforating instrumentality.
70. 2. The combination with a typewriting and a perforating instrumentality for punching a tape according to a predetermined code, said instrumentalities having the same keyboards, of means 75 carried by the typewriting instrumentality to

operatively connect the keys of the latter with those of said perforating instrumentality whereby the actuation of the keys of the typewriting instrumentality will cause the simultaneous actuation of the keys of the perforating instrumentality, said means including a frame structure adapted to support a typewriting instrumentality, horizontally disposed vertically spaced guide members associated with the frame structure and situated above the keyboard of the perforating instrumentality, said guide members having therein a plurality of aligning perforations, a series of rods extending through the perforations in the guide members, said rods having their upper ends pivotally connected to the keys of the typewriting instrumentality and their lower ends disposed in operative relation with respect to corresponding keys of the underlying perforating instrumentality and a foot-pedal controlled means in connection with the frame structure to effect its elevation and disassociate the keys of the typewriter instrumentality with respect to those of the perforating instrumentality, said means including a pivotal mounting for the frame structure, said mounting permitting said frame structure to be swung manually upwardly, and to the rear of said perforating instrumentality, a foot-pedal and an operating connection between the foot-pedal and the pivotal mounting whereby to lift said frame structure a short distance 30 above said perforating instrumentality.

3. The combination with a typewriting and a perforating instrumentality for punching a tape according to a predetermined code, said instrumentalities having the same keyboards; of means carried by the typewriting instrumentality to connect operatively the keys of the latter with those of said perforating instrumentality, whereby the actuation of the keys of said typewriter instrumentality will cause the simultaneous actuation of the corresponding keys of the perforating instrumentality, said means including a hinged frame structure adapted to support the typewriter above the perforating instrumentality, a guide member carried by the frame structure 40 and over-hanging the keyboard of the perforating instrumentality, a series of rods extending through said guide member, said rods having their upper extremities pivotally connected to the keys of the typewriting instrumentality and their lower ends disposed in operative relation with respect to corresponding keys of the underlying perforating instrumentality, a foot pedal controlled means in connection with the frame structure to effect elevation of said frame structure 45 and temporarily disassociate the connection between the keys of the two instrumentalities, whereby to permit operation of the keys of the typewriter instrumentality without consequent actuation of those of the perforating instrumentality.

4. The combination with a typewriting and a perforating instrumentality for punching a tape according to a predetermined code, said instrumentalities having the same keyboards; of means carried by the typewriting instrumentality to connect operatively the keys of the latter with those of said perforating instrumentality, whereby the actuation of the keys of said typewriter instrumentality will cause the simultaneous actuation of the corresponding keys of the perforating instrumentality, said means including a hinged frame structure adapted to support the typewriter above the perforating instrumentality, a guide member carried by the frame structure 55 and

and over-hanging the keyboard of the perforating instrumentality, a series of rods extending through said guide member, said rods having their upper extremities pivotally connected to the keys of the typewriting instrumentality and their lower ends disposed in operative relation with respect to the corresponding keys of the underlying perforating instrumentality, a foot pedal controlled means in connection with the frame structure to effect elevation of said frame structure and temporarily disassociate the connec-

tion between the keys of the two instrumentalities, whereby to permit operation of the keys of the typewriter instrumentality without consequent actuation of those of the perforating instrumentality, said last mentioned means including means for swinging the typewriting instrumentality and the means carried thereby upwardly and to the rear of said perforating instrumentality. 5
